UNITED STATES PATENT OFFICE

RALPH S. MEGATHLIN, OF SOMERVILLE, MASSACHUSETTS, ASSIGNOR TO UNITED SHOE MACHINERY CORPORATION, OF PATERSON, NEW JERSEY, A CORPORATION OF NEW JERSEY

SHOE HEEL AND METHOD OF ASSEMBLING AND ATTACHING THE SAME

Application filed October 10, 1924. Serial No. 742,860.

This invention relates to shoe heels and methods of assembling and attaching the same.

An object of the invention is to reduce the labor cost of assembling and attaching an extensively used type of heel, which comprises a base section made of leather or any suitable composition or material having the characteristics desired in a heel base, and a rubber top lift, without detriment to the quality of the finished shoe in which the heel is embodied. With this object in view the invention comprises a method of assembling and temporarily securing together, with a minimum of labor, an unattached heel base and a rubber heel, which consists in inserting one or more fastenings in the outer face of the base, leaving the end or ends of said fastening or fastenings projecting, placing the rubber heel upon the projecting end or ends in register with the base, and pressing the rubber heel upon the fastening means, which enter the rubber readily and secure the elements of the heel together temporarily sufficiently to withstand the ordinary handling to which the heel is subjected prior to its attachment to a shoe. The fastenings used may be of any suitable character and may be inserted in the base section in any desired manner. It has been found convenient and practical to use for this purpose a machine of the type disclosed in United States Letters Patent No. 910,147, granted Jan. 19, 1909, which is known to the trade as the wire grip tacker. This machine cuts off and drives a headless metallic fastening made from a continuous wire having a corrugated or roughened surface. The machine is very rapid in its operation and makes it possible to drive a plurality of fastenings, for example, three, as herein shown, very quickly. No cement is required and under some conditions it may be sufficient to use a single fastening, but under other conditions it will be found preferable to use a plurality of fastenings and, when this is done, the base and the rubber heel are not only kept in assembled relation but are prevented from rotative movement relative to each other, which is an aid in locating the

heel easily and quickly in the heel attaching machine.

The scope of the invention further comprises a method of assembling and attaching rubber heels and leather or composition bases which comprises combining and assembling a rubber heel and an unattached base in their proper positions relative to each other by attaching means forced into their contacting surfaces and then nailing both the rubber heel and the base simultaneously to a shoe. When this procedure is employed it is only necessary to drive a single gang of heel attaching nails, and the assembling and attachment of the heel are effected with the least possible number of easy operations and, consequently, at a minimum labor cost.

In another aspect of the invention an improved unattached heel is provided consisting of a base section and a rubber top lift secured together by fastenings forced into their contacting faces. No cement is required to maintain the base and top lift in assembled relation and, inasmuch as the fastenings penetrate only the contacting faces of the base and top lift, there is no defacement of any of the exposed surfaces of the heel, as is the case when assembling nails or other fastenings are driven through either of the exposed faces of an assembled heel.

It should be understood that the term "rubber", as used in this specification and the appended claims, is intended to denote any suitable elastic or resilient material or composition, such as those commonly used in the manufacture of cushion heels.

One specific mode of practising the method of the present invention and one example of the invention as embodied in a heel will now be described in connection with the accompanying drawings, in which—

Fig. 1 is a perspective view of a heel base with fastenings inserted in its outer face and projecting therefrom;

Fig. 2 shows a machine stapled for inserting the fastenings;

Fig. 3 shows a rubber heel registered with the base and forced upon the projecting ends of the fastenings;

Fig. 4 shows the assembled heel located

upon a shoe in a heeling machine, ready for the heel attaching operation; and

Fig. 5 shows the heel attached to a shoe.

Referring now to the drawings, 10 indicates a leather or composition heel base of any usual or desired form. At suitable positions three fastenings 12 are forced or driven into the outer face of the base 10. It is not necessary that the location of the 10 fastenings be determined with great exactness but they should be so placed as not to interfere with the washers 14 in the rubber top lift 16 when the latter is registered with the base section, nor with the heel attaching 15 nails 18 which are to be driven through the said washers.

In Fig. 2, 20 indicates a fastening inserting machine of the type above referred to, which, as before stated, is well known to the 20 trade as the wire grip tacker. This machine cuts off from a continuous wire 22 a headless metallic fastening having a corrugated or roughened surface and forces or drives it into the work held upon a work support 24. This 25 machine is very rapid in its operation and, inasmuch as exactness in the location of the fastenings 12, with respect to the heel base section 10 is not required, the three fastenings shown can be inserted very quickly. A single 30 operator, therefore, with a machine of this kind, can prepare a very large number of heel bases in a day. After a heel base is prepared, as shown in Fig. 1, a rubber heel or 35 top lift 16 is placed upon the projecting ends of the fastenings 12, in register with the base, and pressed or forced upon the fastening means, which enter the rubber readily and 40 secure the elements of the heel together temporarily, sufficiently to withstand the ordinary handling to which the heel is subjected prior to its attachment to a shoe.

The assembled heel, as illustrated in Fig. 3, is handled as a unit and may be attached to a shoe with a single gang of attaching nails 45 driven at a single operation. In Fig. 4, 26 indicates a well known commercial type of heel attaching machine in which a shoe 28 is supported upon a jack and the assembled heel is held in a suitable holder. The shoe 50 and the composite heel are registered properly with each other, pressed together, and the attaching nails 18 driven by a single stroke of the machine.

According to the practice usually followed 55 in shoe factories where heel bases and rubber heels are attached to shoes by the single nailing method, the rubber heel and the base are coated with rubber cement, which must be allowed partially to dry, and are then assembled and pressed together to produce the composite heel for use in the heeling machine; the cement being required to keep the parts 60 of the heel together in proper relationship while the heel is being handled in preparation 65 for attachment. My improved method elimi-

nates the expensive cement and the waste of time required for the drying thereof, and the time required for the insertion of the fastenings 12 is materially less than is required even for the coating of the two parts of the heel 70 with cement.

Wherever, in the foregoing specification and the appended claims, reference is made to the outer face of a heel base it should be understood that the face of the base to which the rubber heel is to be applied is meant. This is in accordance with common usage in the art and this language, wherever it occurs, should be construed accordingly. Likewise it should be understood that the inner face of the 80 rubber heel or top lift is the attaching face, which is placed in contact with the outer face of the base.

Having described the invention, what is claimed as new and desired to be secured by 85 Letters Patent is:

1. The method of assembling and temporarily securing together unattached heel bases and rubber heels which consists in inserting a fastening from and into the outer face of an 90 unattached heel base, leaving the end of said fastening projecting from said face, placing a rubber heel in register with the base, and pressing the rubber heel upon the projecting end of the fastening to secure the rubber heel 95 and base together temporarily sufficiently to withstand ordinary handling.

2. The method of assembling and temporarily securing together unattached heel bases and rubber heels which consists in inserting a 100 plurality of spaced apart fastenings from and into the outer face of an unattached heel base, leaving the ends of said fastenings projecting from said face, registering a rubber heel with said base, and forcing the rubber heel upon the projecting ends of the fastenings to secure the rubber heel and the base together temporarily sufficiently to prevent 105 relative angular displacement or separation of the rubber heel and base in ordinary handling.

3. The method of attaching rubber and leather heels to shoes which consists in combining and assembling a rubber top lift and a leather or composition base in their proper 110 position relative to each other by attaching means forced from and into the outer face of the base and the inner face of the rubber top lift, and thereafter firmly securing both elements to a shoe.

4. The method of attaching rubber and leather heels to shoes, without the use of cement, which consists in securing the rubber heel to the leather base by fastenings forced from and into the outer face of the base and 115 the inner face of the rubber heel, and thereafter nailing both the rubber heel and the base simultaneously to a shoe.

5. The method of assembling and attaching 120 heel bases and rubber heels which consists in 125

inserting a fastening from and into the outer face of a heel base, leaving the end of said fastening projecting from said face, assembling a rubber heel in register with the base, 5 pressing the rubber heel upon the projecting end of the fastening to secure the rubber heel and base together temporarily, and thereafter attaching the assembled rubber heel and base to a shoe by nails driven through both the 0 rubber heel and the base.

6. An unattached, cementless heel for boots or shoes comprising a leather or composition base and a rubber top lift temporarily secured together by driven fastenings which 5 penetrate only the contacting faces of the base and the top lift.

7. An unattached, cementless heel for boots or shoes comprising a leather or composition base and a rubber top lift temporarily secured together by headless, corrugated fastenings which penetrate only the contacting faces 0 of the base and the top lift.

In testimony whereof I have signed my name to this specification.

5 RALPH S. MEGATHLIN.
